CLAIM

The ornamental design for a liquid precision discharge control machine, as shown and described.

DESCRIPTION

FIG. 1 is a front view thereof, showing a liquid precision discharge control machine of my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is an oblique view thereof.

In the drawings, the broken lines depict portions of the liquid precision discharge control machine that form no part of the claimed design.
